UNITED STATES PATENT OFFICE

BENJAMIN F. ZEHNER, OF ASHLAND, OHIO

DOOR OPENING DEVICE

Application filed March 19, 1930. Serial No. 437,156.

My present invention has reference to a thereof, I fix a suitable box-like housing 8 simple, new and novel mechanism for automatically swinging the doors of a garage to which is round in plan and which is comparatively small. In each of the housings open position by the weight of an automobile upon a depressible platform when approaching the garage, and likewise again 55 swinging the doors to open position when the vehicle within travels on the platform in leaving the garage.

10 To the attainment of the above broadly recited objects the invention resides in the improvement hereinafter described and definitely claimed.

In the drawings:

15 Figure 1 is a horizontal sectional view through a garage equipped with the improvement.

Figure 2 is a sectional view approximately on the line 2—2 of Figure 1.

20 Figure 3 is a detail face view looking toward the front of the garage.

Figure 4 is a plan view of the operating mechanism with the platform removed.

25 Figure 5 is a substantially central longitudinal sectional view through the construction illustrated by Figure 4, and showing the platform thereon.

Figure 6 is a detail sectional view approximately on the line 6—6 of Figure 4.

30 Referring now to the drawings in detail, the numeral 1 designates an ordinary type of garage and 2—2 the outwardly swinging doors therefor. These doors are hinged in the usual manner to the garage, as indicated by the numeral 3.

In carrying out my invention I arrange 35 in a line longitudinal with the plane of the garage a depressible platform 4. The platform is elongated and extends a suitable distance both within and without the garage. The top board of the platform has its ends hinged to links 5, the said links in turn having their lower or depending ends hingeably supported, as at 6. The platform is 45 normally retained in horizontal position through the medium of spring means 7, and the platform if of a width whereby one of the wheels of the vehicle can freely travel thereover.

50 Beneath each door 2 at the hinged edge

8 which is round in plan and which is comparatively small. In each of the housings there is an upstanding lug 9, the outer face of each of the lugs being formed with an annular depression in which is journaled a trunnion 10 on the lower face of a bevel gear 11. Each of the bevel gears on its outer face is formed with spaced upstanding plates 12 that receive the doors 2 therebetween and which are bolted or otherwise secured to the doors by means 13. Obviously the lower edge of the door 2, through which the depressible platform 4 passes is preferably cut-away, but this cut-away space 65 may be filled by a lateral extension on the second door, as disclosed by Figure 3 of the drawings.

There is journaled transversely through bearing openings in the inner faces of the 70 housings 8 and likewise through the lugs 9 a shaft 14. This shaft has a cranked portion 15 which freely passes through a bearing 16 on the under face of the platform 4. The spring means 7 normally hold 75 the crank 15 in an upright vertical position.

Freely mounted on the shaft 14 and engaging with the teeth of the gear 11 there are similar gears 17 and 18, respectively, the said gears, of course, being arranged in 80 the housings 8. Each of these gears on its outer or non-toothed face is formed with a lug 19, and the shaft 14 has passed therethrough pins 15 that are designed for contact with the oppositely disposed active 85 faces of the lugs 19 on the respective gears 17 and 18.

By an arrangement as above described it will be noted that when a vehicle approaches 90 the garage and one of the wheels thereof rides on and depresses the platform 4, the same will be moved downwardly by the weight of the machine, causing the crank portion 15 of the shaft 14 to turn the said shaft. This brings one of the pins on the 95 shaft into engagement with the lug on one of the gears, say the gears 17, and these turning gears revolve the gear 11 which will swing the doors to open position. After the vehicle travels off the platform into the 100

garage the spring 7 will swing the platform to its normal position, and the operator of the car will swing the doors to closed position. This causes the gears 11 to return the gears 17 and 18 to initial position, that is to bring the lugs thereof opposite and into contact with the pins on the shaft. When the vehicle is to be driven out of the garage, one of the wheels thereof will contact with the inner end of the platform and depress the same and turn the shaft 14 in an opposite direction to that previously described. The gears 18 now become the active gears as the lugs thereon are contacted by the pins on the shaft, so that the said gears 18 will cause the turning of the gears 11 and thus again swing the doors to outward open position. After the vehicle travels off the platform the doors are again closed by the driver of the machine which returns the gears 17 and 18 to initial positions.

The simplicity of my construction and the advantages thereof will, it is thought, be perfectly apparent without further detailed description. Obviously I do not wish to be restricted to the precise details herein set forth and, therefore, hold myself entitled to make such changes therefrom as fairly fall within the scope of what I claim.

Having described the invention, I claim:
The combination with outwardly swinging hinged doors for a garage or the like, of a platform arranged beneath one of the doors and extending in opposite directions therefrom, pivoted depending links at the ends of the platform, elements to which the lower ends of the links are pivoted, spring means influencing the platform to normally sustain the same in horizontal position, a shaft journaled transversely below the platform having a cranked portion, a bearing on the under face of the platform for the cranked portion of the shaft, housings beneath the hinged edges of the doors, an upstanding lug in each housing, said shaft having its ends received in the housings and finding bearings through the lugs, a pair of facing gears loose on the shaft in each of the housings, each of said gears having lugs on the outer face thereof, pins on the shaft to contact with the opposite faces of the lugs on the respective pairs of gears, a gear overlying each pair of gears, in mesh therewith and journaled on the lugs, and said gears having upstanding plates which pass through the top of the housings, receive the doors therebetween and fixedly connected to said doors at the hinged edges thereof.

In testimony whereof I affix my signature.
BENJAMIN F. ZEHNER.
